US0D1087220S

(12) United States Design Patent (10) Patent No.: US D1,087,220 S
Hu et al. (45) Date of Patent:  Aug. 5, 2025

(54) CASH REGISTER

- (71) Applicant: Fujian LANDI Commercial Equipment Co., Ltd., Fuzhou (CN)
- (72) Inventors: Changfa Hu, Fujian (CN); Yunbin Zheng, Fujian (CN); Xiaoquan Zhang, Fujian (CN); Zhiyong Ye, Fujian (CN); Jie Liu, Fujian (CN)
- () Term: 15 Years
- (21) Appl. No.: 35/520,699
- (22) Filed: Mar. 20, 2024
- (80) Hague Agreement Data
- Int. Filing Date: Mar. 20, 2024
 Int. Reg. No.: DM/236664
 Int. Reg. Date: Mar. 20, 2024
 Int. Reg. Pub. Date: May 3, 2024
